UNITED STATES PATENT OFFICE.

LENNA L. ROSS, OF BOSTON, MASSACHUSETTS.

DESIGN FOR AN ADVERTISING POST CARD.

Application filed March 20, 1924. Serial No. 9,010. Term of patent 3½ years.

To all whom it may concern:

Be it known that I, LENNA L. Ross, a citizen of the United States, residing at Boston, in the county of Suffolk and State of Massachusetts, have invented a new, original, and ornamental Design for an Advertising Post Card, of which the following is a specification, reference being had to the accompanying drawing, forming a part thereof.

The figure is a front elevation, showing my new design.

I claim:

The ornamental design for an advertising post card, as shown.

LENNA L. ROSS.
